[57] CLAIM

The ornamental design for a combined dispensing bottle and cap, as shown and described.

DESCRIPTION

FIG. 1 is a front elevation of a combined dispensing bottle and cap therefor, showing my new design;
FIG. 2 is a right side elevation thereof;
FIG. 3 is a left side elevation thereof;
FIG. 4 is a top plan view thereof;
FIG. 5 is a bottom plan view thereof; and,
FIG. 6 is an exploded perspective view thereof with the cap member shown separately for clarity of illustration.

FIG. 1

FIG. 2

FIG. 3

FIG. 4

FIG. 5

FIG. 6
